(57) **CLAIM**

The ornamental design for anchored mat having a reservoir to collect liquids, as shown and described.

DESCRIPTION

FIG. 1 is a top plan view of the anchored mat showing the design.

FIG. 2 is a left side cross-section elevational view thereof showing the contours of the anchored mat;

FIG. 3 is a top isometric view of the anchored mat showing throughholes along the outer perimeter of the anchored mat and channels at the corners;

FIG. 4 is a bottom plan view of the anchored mat thereof showing throughholes along the perimeter of the mat; and, FIG. 5 is a right side cross-section elevational view showing my design.
